MEANS FOR ATTACHING WOOD HEELS TO SHOES

William Clark Goodchild, Jr., Beverly, Mass., assignor to United Shoe Machinery Corporation, Flemington, N. J., a corporation of New Jersey

Application June 26, 1942, Serial No. 448,534

4 Claims. (Cl. 85—28)

This invention relates to the manufacture of shoes and is described herein with reference to improved means for attaching heels to shoes on the last.

In the manufacture of women's shoes it is common practice to attach a heel to a shoe by the use of a permanent screw or other suitable fastener or fastening driven through a passage extending heightwise through the cone of a last upon which the shoe is mounted. In order to insure that the screw shall effectively hold the heel on the shoe, it is desirable that the head of the screw be of substantial size. Accordingly, the passage in the last through which the permanent screw is driven has to be of large diameter and such a passage tends to weaken the last. Because of the above and other considerations, shoe manufacturers have been very reluctant to drill their lasts to accommodate permanent screws.

The number of shoes the heels of which are attached by permanent screws driven through lasts, therefore, is negligible as compared with the number of shoes the heels of which are attached by the use of the commercially accepted temporary screw attachers such as disclosed in United States Letters Patent No. 1,615,258, granted January 25, 1927, on an application filed in the name of Maurice V. Bresnahan. The hole in the last for receiving the temporary attaching screw, which hole is approximately $\frac{7}{32}$ of an inch in diameter and has little tendency to weaken the last, is too small to accommodate a screw having a head sufficiently large to hold the screw at the inside of the shoe.

It is an object of the present invention to provide for quickly and effectively attaching heels to shoes mounted upon lasts of the general construction disclosed in said Letters Patent No. 1,615,258, by the use of permanent fastenings, without having materially to change the construction of said lasts.

In accordance with a feature of the present invention there is provided for use in attaching a heel to a shoe a fastening unit comprising a headed metallic fastener or fastening, having a shank, and a large collar through a bore of which said shank passes, said collar being held in frictional engagement with a shank portion of the fastener which is spaced a substantial distance from the head of the fastener and being engaged by the head of the fastener during the heel-attaching operation and forming therewith a large head, portions of the shank of the fastener adjacent to said head being smaller than the bore of the collar in order that the collar can freely

tilt laterally with relation to the fastener as it is forced into the work, said collar being held against movement upon the head of the fastener by the work when the fastening unit has been driven into the same.

The various features of the invention will now be described and appreciated from the following detailed description read in connection with the accompanying drawing, in which

Fig. 1 shows in side elevation the heel end of an improved last, partly in section, and an improved fastening unit assembled therewith, during an early stage in the manufacture of a shoe;

Fig. 2 is a side view, partly in section and partly broken away, showing a heel in the process of being attached to the shoe;

Fig. 3 is an enlarged side view, partly in section, of the fastening unit at the time it is assembled with the last;

Fig. 4 shows the fastening unit of Fig. 3 at a later stage in the manufacture of the shoe;

Fig. 5 is a side view, partly in section and partly broken away, showing the shoe in the process of having its heel attached by the use of a modified fastening unit; and

Figs. 6 and 7 are enlarged side views, partly in section, respectively showing the modified fastening unit at the time it is assembled with the last and after it has been driven into the work.

The invention is described with reference to attaching a heel 20 (Figs. 2 and 5) to a shoe 22 which is mounted upon a last 24 (Figs. 1, 2 and 5), by the use of a fastening unit 26 (Figs. 3 and 4), or 28 (Figs. 6 and 7). The fastening unit 26 comprises a drive screw 30 (Figs. 1, 2, 3 and 4) and a frusto-conical collar 32, and the fastening unit 28 comprises a drive screw 34 (Figs. 5, 6 and 7) and a frusto-conical collar 36. The last 24, which is provided with a cylindrical passage 38 approximately $\frac{7}{32}$ of an inch in diameter, is identical with the last disclosed in the above-mentioned Letters Patent No. 1,615,258 except for the fact that said passage terminates short of the heel-seat 40 of the last which is counter-bored to form a pocket 42. The pocket 42 may be considered as an enlarged extension of the passage 38 or, alternatively, the passage 38 may be considered as terminating at the pocket 42 the bottom of which constitutes a collar-supporting ledge or shoulder 43 (Fig. 1).

The drive screw 30 of the fastening unit 26 has a steeply threaded shank 44 (Figs. 3 and 4) and a relatively small head 46 of slightly less diameter than the diameter of the passage 38. The collar 32 is bored to provide a cylindrical passage

or hole 48 and is initially assembled in frictionally binding relation upon the screw 30, as shown in Fig. 3, the diameter of the cylindrical passage being approximately equal to the diameter of the major portion of the shank of the screw. The bore of the collar 32 also comprises a concave spherical surface 50 which, during the heel-attaching operation, is engaged by a spherical surface or bottom 52 of the screw head 46. The portion of the shank 44 of the screw 30 adjacent to the head 46 has a diameter somewhat less than that of the cylindrical passage 48 of the collar 32, the construction of the collar and the screw being such that during the heel-attaching operation the collar may be tilted laterally upon the head of the screw so that in the finished shoe a top face 54 of the collar shall be approximately parallel to the inside face 56 (Figs. 2 and 5) of the heel seat of the shoe. The collar 32, which may be described as being mounted for universal movement upon the head 46 of the screw 30, together with said head, forms an enlarged head for increasing the holding power of the screw at the inside of the shoe.

During the manufacture of the shoe the fastening unit 26, shown in Fig. 3, is dropped into the pocket 42 and the passage 38 of the inverted last 24 supported upon a last pin 58 and assumes the position shown in Fig. 1. The construction of the last 24 and the fastening unit 26 is such that when the collar 32 rests upon the shoulder 43 of the last, the point of the drive screw 30, which is secured against falling through the passage 38 by the collar, is located just beneath the plane of the heel seat 40 of the last. An insole 60 is then tacked to the bottom of the last 24 and the shoe is built up in the usual manner upon the last, the screw 30 being held in captive relation in the last during such process by the collar 32. After the heel-seat portion of the shoe 22 has been fitted, the heel 20 is clamped against said heel seat by the use of a machine such, for example, as disclosed in United States Letters Patent No. 2,034,741, granted March 24, 1936, on an application filed in the name of Francis L. Brandt, and the screw 30 is then driven through the heel seat of the shoe and into the heel by a driver 62 to attach the heel to the shoe. During the heel-attaching operation the screw 30 is forced through the collar 32 until the head 46 of the screw engages the surface 50 of the collar, at which time the relation between the two members is as shown in Fig. 4.

The axis of the driver-receiving passage 38 is inclined at an angle α (Fig. 1) to a line disposed at right angles to the heel-seat face 40 of the last, such angle representing the angle through which the collar 32 swings or tilts upon the head of the screw during the heel-attaching operation, thereby insuring that in the finished shoe the top face 54 of the collar 32 shall be parallel to the inside face 56 of the heel seat of the shoe. By providing for tilting movement of the collar 32 upon the head 46 of the screw 30, as above described, it will be clear that the screw does not have to be driven as far into the insole 60 of the shoe as it would have to be driven were the collar prevented from tilting on the head of the screw. In order to insure that in the finished shoe the head 46 of the screw 30 shall not extend beyond the top face 54 of the collar 32 even though the axis of the collar be disposed at a substantial angle to the axis of the screw, the depth of the recess 50 which houses the head of

the screw is somewhat greater than the thickness of said head, as best shown in Fig. 4.

The fastening unit 28 (Figs. 5, 6 and 7) may be used in place of the above-described fastening unit 26 to attach the heel 20 to the shoe 22, the shoemaking procedure in both cases being the same. The head 64 of the screw 34 is of frusto-conical shape and during the heel-attaching operation is forced into a complementally shaped frusto-conical portion 66 of a bore of the collar 36. The shank 68 of the screw 34, including the portion of the shank adjacent to the head 64, has a diameter equal to that of a cylindrical portion 70 of the bore of the collar and, accordingly, said collar cannot tilt to any extent upon the head of the screw during the heel-attaching operation.

It will be understood that, if desirable, a conventional screw (not shown) may be substituted for either of the screws 30, 34, in which event a rotatable screw driver (not shown) will be used.

The method practiced in attaching wood heels to shoes by the use of the above fastening unit constitutes the subject matter of a divisional application Serial No. 462,281, filed October 16, 1942.

Having described my invention, what I claim as new and desire to secure by Letters Patent of the United States is:

1. A fastening unit for use in attaching a heel to a shoe comprising a headed metallic fastener having a shank, and a large collar through a bore of which said shank passes, said collar being held in frictional engagement with a shank portion of the fastener which is spaced a substantial distance from the head of the fastener and being engaged by the head of the fastener during the heel-attaching operation and forming therewith a large head, portions of the shank of the fastener adjacent to said head being smaller than the bore of the collar in order that the collar can freely tilt laterally with relation to the fastener as it is forced into the work, said collar being held against movement upon the head of the fastener by the work when the fastening unit has been driven into the same.

2. A fastening unit for use in attaching a heel to a shoe comprising a screw having a small head the bottom of which is spherical, and a larger collar which is mountable upon said head and has a bore a portion of which is complemental to the spherical bottom of said head and another portion of which is substantially larger than the shank of the screw adjacent to said head, the collar during the heel-attaching operation being tiltable upon the head and forming with said head a large fastening unit head, said collar being held against movement upon the head of the screw by the work when the fastening unit has been driven into the same.

3. A fastening unit for use in attaching a heel to a shoe comprising a screw having a head the bottom of which is spherical, and a larger collar which is held frictionally to the shank of the screw and has an opening comprising a concave spherical face complemental to the spherical bottom of said screw head and a passage which is larger than the shank of the screw adjacent to said head, the screw during the heel-attaching operation being forced through the collar until the spherical bottom of its head engages the concave spherical face of the collar, the collar being tiltable upon said screw head during the heel-attaching operation and together with the screw head constituting a large fastening unit head, said collar being held against movement upon the

head of the screw by the work when the fastening unit has been driven into the same.

4. A fastening unit for use in attaching a heel to a shoe comprising a screw having a head, and a larger collar which is secured frictionally to the shank of the screw and which during the heel-attaching operation is engaged by said head and forms therewith a fastening unit head, said collar having a cylindrical bore of a diameter greater than that of a shank portion of the screw located 10 adjacent to the screw head thereby enabling the

collar to tilt laterally upon the screw head during the heel-attaching operation and thus insuring that in the finished shoe an upper face of the collar shall be parallel to the inside face of the heel seat of the shoe irrespective of the angle at which the screw is driven into said heel seat, said collar being held against movement upon the head of the screw by the work when the fastening unit has been driven into the same.
